UNITED STATES PATENT OFFICE

158,551

SALAD SERVER

Paul W. Buechler, Detroit, Mich.

Application June 4, 1948, Serial No. 146,765

Term of patent 14 years

(Cl. D44—4)

To all whom it may concern:

Be it known that I, Paul W. Buechler, a citizen of the United States of America and residing at Detroit, county of Wayne, State of Michigan, have invented a new, original, and ornamental Design for a Salad Server, of which the following is a specification, reference being made to the accompanying drawings, forming part thereof.

Fig. 1 is a top plan view of a salad server, showing my new design;

Fig. 2 is a side view;

Fig. 3 is a bottom plan view; and

Fig. 4 is an inverted side view opposite the side shown in Fig. 2.

I claim:

The ornamental design for a salad server, substantially as shown and described.

PAUL W. BUECHLER.
